Attorney

UNITED STATES PATENT OFFICE.

CLEMENT BROWN, OF BIRMINGHAM, ENGLAND.

CARBURETOR FOR INTERNAL-COMBUSTION ENGINES.

Application filed September 27, 1920, Serial No. 413,150, and in Great Britain September 13, 1919.

This invention relates to improvements in carburetors.

It is an object of the invention to provide means combined with or forming a part of the 5 throttle valve for automatically varying the amount of additional air which is introduced into the fuel mixture and to render this admission of air dependent upon the position of the throttle valve.

10 It is also an object of the invention to close or open respectively to a varying degree by means of a throttle valve an orifice which communicates with the atmosphere and which leads to a fuel mixture delivery space.

15 Another object of the invention is to improve the construction of a throttle valve in carburetors by simplifying the same, and to control by the simplified valve not only the admission of additional air, but also the admission 20 of fuel mixture into a fuel delivery chamber.

25 It is furthermore an object of the invention to provide a throttle valve with means whereby the residue of the mixture of fuel remaining from a former operation within a fuel delivery chamber may be automatically removed through the suction which is produced by the first strokes of the engine.

With these and numerous other objects in 30 view the invention is illustrated in the accompanying drawing and described in the following specification.

Fig. 1 is an elevation of the principal parts of a carburetor according to the present invention;

35 Fig. 2 is a vertical sectional view through the same;

Fig. 3 is a sectional vertical view at a right angle to the plane in which the sectional view 40 of Fig. 2 is taken.

The carburetor may comprise a float chamber 1 or fuel supply casing which stands in communication with a fuel conduit 2, through which the fuel flows into a transverse bore 3 leading to a bore in plug *n* secured to a part of the carburetor casing 4. The plug *n* is provided with a vertical channel 5, and the fuel, after passing through the channel, enters through a bushing *g* into the lower portion 45 of the mixture chamber. The bushing *g* is preferably seated in the casing 4 by being pressed against a shoulder through a spring *m*, so as to avoid the necessity of providing these parts with screw threads. The part *f* 50 of the fuel mixture chamber communicates

with a chamber 6, which is provided with an opening *h* for the admission of air.

The flow of fuel may be regulated by a needle valve *i* having near its upper end a threaded portion *j*, which is seated in a screw plug 7, 60 passing through the top plate 8 of the casing 4. By means of a spring 9 between the plug and a head 10 of the needle valve, the latter will always be yieldingly retained in adjusted position, but still may be readily adjusted by 65 merely turning the top 10 of the valve. It will be seen, therefore, that owing to the provision of this adjustable needle valve the amount of fuel which enters from the chamber 1 may be adjusted entirely independent of 70 any adjustment of the other parts of the carburetor.

The chamber *f* communicates through a channel 11 with a chamber 12 of the casing and in which a throttle valve *c*, preferably in 75 the form of a straight slide or plate, is movably disposed. The mixture of fuel and air admitted through the bushing *g* and opening *h*, respectively, will flow through this passage 11 into the chamber 12 and upon proper 80 adjustment of the throttle valve plate *c* this mixture will enter a channel *a* in the throttle valve and will arrive in a transverse bore *b* or fuel delivery chamber of said valve.

The wall of the casing 4 may be provided 85 with a circular flange 13 to receive a delivery pipe (not shown) for conveying the fuel mixture to the engine. The opening 30 in this wall of the casing 4, and which is surrounded by the flange 13, is in opposition to the opening 31 in the other wall of the carburetor to 90 permit the air to flow straight through the carburetor upon proper positioning of the plate *c*.

The throttle valve plate *c* is shown to be 95 forced down by one or more springs 14, which are seated in suitable sockets 15 of the valve plate, and which are guided by means of screw pins 16, held in the cover 8 of the casing 4. A cable 7, may be used for effecting a sliding 100 movement of the valve plate *c*, whereby the passage *a* may be brought out of communication with the passage 11, which leads from the chamber *f* into the chamber 12. Any other means may be used for effecting this 105 displacement or for permitting the throttle valve plate *c* ordinarily to return to the position in which it is shown in Fig. 1.

One of the walls of the casing 4 is provided 110 with an air inlet opening *d* which ordinarily

does not communicate with the fuel delivery chamber *b*, and the mixture of fuel, therefore, will not be influenced by the additional air which may flow through the opening *d*.
5 If, however, the throttle valve *c* is lowered, to a predetermined point the chamber *b* in the same will be brought into communication with the opening *d* and the vacuum or partial vacuum created in said chamber through the 10 suction of the engine will be partly relieved through the air which enters through the opening *d*. It is obvious that this air admission opening *d* remains in communication with the chamber *b* throughout a range of 15 movement of the valve plate *c* beginning from said point. The location of the air opening *d* may be selected, so that, for instance, it will open into the chamber *b* when the throttle plate *c* is in half closed position, and in the 20 continued movement of the throttle valve to complete closing position, indicated in dotted lines in Fig. 1, this communication between the opening *d* and the chamber *b* is obviously maintained. When, however, the throttle 25 valve is then moved to open position, it will from a certain point in its movement begin to cover the opening *d* and in full open position no air will enter through the opening *d* into the chamber *b*.
30 The rectilinear displacement of the throttle valve to the position indicated in dotted lines in Fig. 1 would bring the channel *a* in the valve out of communication with the passage 11 extending from the chamber *f*. In order 35 to maintain, however, the admission of fuel from the chamber *f* to the chamber *b* at most positions of the throttle valve, a branch groove *e* extends from the channel *a* in a direction at right angle thereto and on the edge 40 of the throttle plate *c*, as shown. It will also be noticed that the cross-sectional area of this grooving *e* varies at different distances from the channel *a*, the capacity at the different distances being accurately determined to control 45 the quantity of fuel admitted to the fuel delivery chamber *b*. With the progress of the closing movement of the valve plate *c*, the cross-sectional area of the grooving *e* decreases, thereby throttling down the amount 50 of fuel which can enter the delivery chamber *b*. This amount of fuel reduced in volume may then be reduced in saturation, when as, for instance, the air opening *d* also registers with the chamber *b* of the plate *c*.
55 Owing to these features of control, to wit, the change of the cross-sectional area of the groove *e* for restricting the inlet of the fuel mixture, the opening *d*, which communicates with the fuel delivery chamber *b*, through a

relatively large range of movement of the valve, very exact means are provided through which the fuel mixture may be regulated in volume and saturation to make it suitable for the requirements of the engine. It is also 60 obvious, however, that under certain conditions, either one of these features of control 65 may be omitted, and still a delicate adjustment of the operative conditions may be obtained through the movement of the throttle valve which automatically restricts a portion 70 of the inlet for the fuel mixture.

I claim:

1. A carburetor having a casing provided on opposite walls with openings in alignment with each other, a throttle valve rectilinearly movable within said casing and having an opening adapted to align with said first named openings in a predetermined position of the valve, a fuel mixture chamber having a passage communicating with the casing and the throttle valve having a passage extending from the opening therein angularly to the direction of the movement of the throttle valve to an edge portion of the valve, said throttle valve passage communicating on the edge 80 portion with recesses of graduated depth adapted to be moved successively into opposition to the passage leading from the fuel mixture chamber and adapted to maintain communication between the fuel mixture chamber and the opening in the throttle valve at any position of said throttle valve. 85

2. A carburetor comprising a casing with aligned openings in opposite walls, a plate shaped throttle valve slidable in the casing 95 and having a fuel delivery chamber adapted to align with said openings in a predetermined position of the valve, a fuel mixture chamber having a passage communicating with the interior of the casing, the throttle 100 valve being provided with a passage extending from its fuel delivery chamber to the edge of the valve, and the throttle valve being provided at its edge with a longitudinally extending groove, the depth whereof varies at 105 different portions of the same, said groove communicating with the outer end of the last named passage in the throttle valve and being adapted to maintain a variable communication between said fuel mixture chamber and said fuel delivery chamber at all positions of the valve and to regulate the fuel passing 110 from the fuel mixture chamber to the fuel delivery chamber.

In witness whereof I have hereunto set my 115 hand.

CLEMENT BROWN.
